CANDY CUP

Mary Frances Currier, 144 Plymouth St.,
San Francisco, Calif.

Filed Oct. 24, 1958, Ser. No. 53,146

Term of patent 14 years

(Cl. D59—2)

FIG.—1

FIG. 3

FIG. 1 is a front perspective view of a candy cup showing my new design;

FIG. 2 is rear elevational view, and FIG. 3 is a front elevational view.

The essential features of my design reside in the parts shown in solid lines on the drawing.

I claim:

The ornamental design for a candy cup, as shown and described.
